[57] CLAIM

The ornamental design for a media unit, as shown and described.

DESCRIPTION

FIG. 1 is a perspective view of the media unit showing our new design;

FIG. 2 is a perspective view thereof wherein the top portion is turned;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of FIG. 1, the difference residing in the shape of the top portion; and,

FIG. 10 is a perspective view of FIG. 9, wherein the top portion is turned.
